UNITED STATES PATENT OFFICE.

HENRY THOMAS HENDERSON, OF CROWELL, TEXAS.

DESIGN FOR A SASH-LOCK.

SPECIFICATION forming part of Design No. 34,626, dated June 4, 1901.

Application filed April 18, 1901. Serial No. 56,523. Term of patent 14 years.

To all whom it may concern:

Be it known that I, HENRY THOMAS HENDERSON, a citizen of the United States, residing at Crowell, in the county of Foard and State of Texas, have invented and produced a certain new and original Design for Sash-locks; and I do declare the following to be a full, clear, and exact description of the invention, such as will enable others skilled in the art to which it appertains to make and use the same.

The invention relates to a new and original design for sash-locks; and it consists of a design of the configuration shown in the accompanying drawings, in which—

Figure 1 is a perspective view of the invention, and Fig. 2 is a plan view.

The leading feature of the design comprises two counterpart disks A and B, extending in opposite directions from a short neck C, from which projects upwardly a stem D, having a flat semicircular piece E. The peripheries of the disks have teeth F.

What I claim is—

The design for a sash-lock, as herein shown and described.

In testimony whereof I have hereunto set my hand in presence of two subscribing witnesses.

HENRY THOMAS HENDERSON.

Witnesses:

J. T. FOSTER,
J. J. WHITLEY.
